UNITED STATES PATENT OFFICE.

CARL R. KLOK, OF CHICAGO, ILLINOIS, ASSIGNOR, BY MESNE ASSIGNMENTS, TO UNITED TABLE-BED COMPANY, A CORPORATION OF VIRGINIA.

TABLE-BED.

1,279,124.

Specification of Letters Patent. Patented Sept. 17, 1918.

Application filed October 31, 1913. Serial No. 798,538.

To all whom it may concern:

Be it known that I, CARL R. KLOK, a citizen of the United States of America, and resident of Chicago, Cook county, Illinois, have invented a certain new and useful Improvement in Table-Beds, of which the following is a specification.

My invention relates to table beds of that kind in which the bed can be unfolded 10 without disturbing the articles on the table.

Generally stated the object of my invention is to provide a novel and efficient table bed of the foregoing general character.

A special object is to provide an improved 15 construction and arrangement whereby the bed may be unfolded without removing the upper wall of the table, and whereby the bed, when unfolded, is supported by the table.

20 It is also an object to provide certain details and features of construction tending to increase the general efficiency of a table bed of this particular character.

To these and other useful ends, my invention 25 consists in matters hereinafter set forth and claimed.

In the accompanying drawings:—

Figure 1 is a longitudinal section of a 30 table bed embodying the principles of my invention, showing the bed folded, being a section on line 1—1 in Fig. 2.

Fig. 2 is a vertical cross section on line 2—2 in Fig. 1.

Fig. 3 is a view similar to Fig. 2, but 35 showing the bed withdrawn from the table, in position for unfolding.

Fig. 4 is a view similar to Fig. 3, but showing the bed unfolded, and also partly within the table for convenience of illustration.

Fig. 5 is a detail section on line 5—5 in Fig. 3.

As thus illustrated, my invention comprises a body A, having fixed legs at a at the 45 four corners thereof. The top B of said body has ends b, a back b¹, a hinged part b² and a fixed upper wall b³. A foot board b⁴ connects the two legs at one end of the table with the two legs at the other end thereof.

50 Panels b⁵ connect the ends of said foot board with the ends b of the table top. The ends of the table are provided interiorly thereof with horizontal tracks C which extend transversely of the table.

55 The bed D comprises a folding angle iron

frame composed of sections d, d¹ and d². Links d³, one at each side, connect the sections d and d¹ together, and similar links d⁴ connect the sections d¹ and d². The links d⁴ are longer than the links d³, to permit the section d to fold between the sections d¹ and d². The section d² is provided with projections d⁵ which engage the tracks C. All of the joints of the bed frame D are of such character; it will be seen, that the said 60 frame will fold upwardly, but when straightened out will not fold downwardly at any point. Thus the bed frame is self sustaining, but to prevent straining thereof, the section d² is provided with fixed legs E at 65 the outer end thereof, and the sections d and d¹ are provided with pivoted legs F and G. The upper ends of the legs F, above the pivots thereof, are connected by links f with the frame links d³. Similar links g 70 connect the upper ends of the legs G, above the pivots thereof, with the links d⁴. Thus the legs F and G are adapted to automatically fold and unfold when the bed frame is 75 folded and unfolded. When the bed is withdrawn from the table, as shown in Fig. 3, the legs E are disposed a distance from the legs of the table; but when the bed is folded inside the table, then the legs E come close to the legs of the table, and are disposed within recesses a⁴ in the front of the 80 table legs. Thus the bed is folded and unfolded without the necessity of disturbing anything on the table.

The table is of proper proportions, and is 85 of the proper height for writing or similar purposes. Also the bed is of the proper height. Practically, both the table and bed, although combined in one unitary structure, are in accordance with standard requirements. The bed frame D is designed to have a metal bed fabric (not shown) stretched thereon. The mattress and bedding are supported in the usual manner, by said fabric. When folded, the links d³ and d⁴ 90 provide space for the mattress and bedding.

With the construction shown, the end section d², which may be called the inner end section of the bed-frame, is always right side up, and when the frame is folded the 95 other end section d is right side up below the middle section, and the entire weight of the bed when thus folded is sustained by the sliding section d² of the frame. Although the bed-frame is permanently con-

nected to the table-body, and is partly supported thereby when in use, still it is also true that the bed-frame is practically entirely outside of the table-body when the bed is 5 unfolded. In this way, the middle section of the bed-frame is available as a seat in entering and leaving the bed, which is the natural and most convenient method of use.

From the foregoing, therefore, it will be 10 seen that the invention involves a practical and simple method of combining a table with a bed, and is devised to solve many of the problems involved in the combining of these two pieces of furniture. It has certain 15 advantages, as previously explained, as well as others, which will be obvious to those skilled in the art, but the invention is not limited to the exact construction shown and described, as the construction can be changed 20 or modified, it will be understood, without departing from the spirit and the fundamental or broader conception of the invention.

What I claim as my invention is:

25 1. A folding bed comprising a furniture body having a fixed top, a three-section folding bed frame whereof the inner end-section thereof is always right side up and horizontal, having devices to connect the sections 30 together, means on said body to support the said permanently right-side-up inner end-section for sliding movement into and out of said body, while the bed remains entirely folded serving to support the end of said 35 inner end-section stationary while the other sections are being folded thereon to bring the outer end-section right side up below the middle section, folding legs to support the frame on the floor, the frame being practically entirely outside of said body when 40 the bed is unfolded, thereby permitting use of said middle section as a seat for entering and leaving the bed, and means on said frame to support a mattress, said sections 45 being each approximately one-third the length of the bed, the outer end-section and the middle section being supported entirely by and horizontally above said sliding inner end-section when the bed is folded, and 50 said body having means to entirely conceal the folded bed below said top.

55 2. A folding bed comprising a body, a folding bed frame having means at opposite sides thereof to slide horizontally on said body, in the direction in which the bed unfolds, preliminary to any unfolding thereof, and which frame is foldable to bring the mattress and bedding entirely inside the 60 rectangular bundle formed thereby, means to limit said sliding movement, folding legs extending below the horizontal plane of said means to support one end of said frame in extended position, said body forming a support for the other end of said bed, and a top 65 adapted to conceal the bed within said body

and form with the latter an ordinary table, said body having end walls provided with guides, said frame having pivotally connected sections one of which slides on said guides, the sliding section being permanently right-side up a fixed distance from the floor, and the other sections of the frame being manually operable to fold and unfold the bed before and after the horizontal movement thereof.

70 3. A folding bed comprising a body, a folding bed frame having means at opposite sides thereof to slide horizontally on said body, in the direction in which the bed unfolds, preliminary to any unfolding thereof, and which frame is foldable to bring the mattress and bedding entirely inside the rectangular bundle formed thereby, folding legs extending below the horizontal plane of said means to support one end of said frame in extended position, said body forming a support for the other end of said bed, and a top 75 adapted to conceal the bed within said body and form with the latter an ordinary table, said body forming one end of the bed and having four fixed legs to support the folded bed within the table, fixed end and side walls rigid with said table legs, and a movable front wall, said walls forming a compartment exclusively for said bed.

80 4. A folding bed comprising a body, a folding bed frame having means at opposite sides thereof to slide outward horizontally on said body, in the direction in which the bed unfolds, preliminary to any unfolding thereof, and which frame is foldable to bring the mattress and bedding entirely inside the rectangular bundle formed thereby, preliminary to inward sliding movement to bring 85 said bundle into the body, means to limit said sliding movement, folding legs extending below the horizontal plane of said means to support one end of said frame in extended position, said body forming a support for the other end of said bed, and a top adapted to 90 conceal the bed within said body and form with the latter an ordinary table, said body having end walls provided with guides, said frame having pivotally connected sections one of which slides on said guides, the sliding section being permanently right-side up a fixed distance from the floor, and the other sections of the frame being manually operable to fold and unfold the bed respectively before and after said inward and outward horizontal movements thereof, said frame 95 folding transversely to bring the head and foot thereof together when the bed is folded.

100 5. A folding bed comprising a body, a folding bed frame having means at opposite sides thereof to slide horizontally on said body, in the direction in which the bed unfolds, preliminary to any unfolding thereof, and which frame is foldable to bring the mattress and bedding entirely inside the 105 rectangular bundle formed thereby, means to limit said sliding movement, folding legs extending below the horizontal plane of said means to support one end of said frame in extended position, said body forming a support for the other end of said bed, and a top 110 adapted to conceal the bed within said body and form with the latter an ordinary table, said body having end walls provided with guides, said frame having pivotally connected sections one of which slides on said guides, the sliding section being permanently right-side up a fixed distance from the floor, and the other sections of the frame being manually operable to fold and unfold the bed respectively before and after said inward and outward horizontal movements thereof, said frame 115 folding transversely to bring the head and foot thereof together when the bed is folded.

120 6. A folding bed comprising a body, a folding bed frame having means at opposite sides thereof to slide horizontally on said body, in the direction in which the bed unfolds, preliminary to any unfolding thereof, and which frame is foldable to bring the mattress and bedding entirely inside the 125 rectangular bundle formed thereby, means to limit said sliding movement, folding legs extending below the horizontal plane of said means to support one end of said frame in extended position, said body forming a support for the other end of said bed, and a top 130 adapted to conceal the bed within said body

tangular bundle formed thereby preliminary to inward sliding movement to bring said bundle into the body, means to limit said sliding movement, folding legs extending 5 below the horizontal plane of said means to support one end of said frame in extended position, said body forming a support for the other end of said bed, and a top adapted to conceal the bed within said body and 10 form with the latter an ordinary table, said body having end walls provided with guides, said frame having pivotally connected sections one of which slides on said guides, the sliding section being permanently right-

side up a fixed distance from the floor, and 15 the other sections of the frame being manually operable to fold and unfold the bed respectively before and after said inward and outward horizontal movements thereof, 20 said frame folding transversely about four transverse axes to bring the head and foot thereof together when the bed is folded.

Signed by me at Chicago, Illinois, this 18th day of October, 1913.

CARL R. KLOK.
